UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,742.

To all whom it may concern:

Be it known that I, FRED S. CARR, a citizen of the United States, and a resident of Newton, in the county of Middlesex and 5 Commonwealth of Massachusetts, have invented an Improvement in Fasteners, of which the following description, in connection with the accompanying drawings, is a specification, like characters on the drawings representing like parts.

This invention pertains to improvements in separable fasteners. It is among the objects of the invention to provide a separable fastener of simple construction, great durability and of superior holding power.

In the drawings, which show a preferred form of one illustrative embodiment of my invention:—

Figure 1 is an elevation of two pieces of 20 fabric to which the stud and socket members of a preferred form of separable fastener are attached;

Fig. 2 is a section on the line 2—2 of Fig. 1;

Fig. 3 is a front elevation of the preferred 25 form of socket illustrated in Figs. 1 and 2;

Fig. 4 is an elevation of the preferred form of stud shown in Figs. 1 and 2; and

Fig. 5 is a section through the fastener on the line 5—5 of Fig. 1.

Referring to the drawings and to the preferred form of my invention selected for 30 illustrative purposes, I have shown a stud including a head 6, a neck 7 and a base 8, and secured to the stud-carrying fabric 9 in any suitable way as by stitching 10. I have shown a cooperating socket including a casing 11 providing a stud-receiving plate 12 having a stud-receiving aperture 13 therein and containing a spring 14 presenting two 35 portions intersecting the stud-receiving aperture 13. The preferred form of spring will be more fully described hereinafter.

The preferred form of socket illustrated is 40 sewn to the socket-carrying fabric 15 by 45 stitches 16. Where my invention is utilized in connection with fastening elements adapted to be sewn to their carrying fabrics, I prefer to make the casing 11 in one piece and to provide for holding in the spring 14 by a 50 flanged-over rim 17 of the casing. The stud-receiving aperture 13 is preferably notched at one side providing the recess 18 communicating with the stud-receiving aperture 13 and adapted to permit the stud to shift laterally in the socket to a small extent, sufficient

to prevent separation of stud and socket by the resolution of forces arising from lateral strain between stud and socket urging the stud toward the notch, or in the general direction of the notch, the notch, however, 60 preferably being of such dimension relative to the neck and head of the stud that separation of stud and socket may be effected even while under considerable lateral strain by a convenient tipping movement at an angle 65 somewhat greater than that likely to be produced by the resolution of forces arising from lateral strains in the direction indicated.

The spring 14, as before described, preferably 70 intersects the stud-receiving aperture 13 at opposite sides thereof as at 19 and 20. Between these portions, the spring extends adjacent to the peripheral wall of the socket, underlying the flange 17 at 21. At the other 75 side of the portions 19 and 20 the spring underlies the flange 17 at 22 and 23, being bent backwardly and outwardly until they again underlie the flange 17 at the sides of the casing at 24 and 25, these preferably 80 being, as illustrated, adjacent terminal reverse bends extending outwardly and downwardly to the ends of the spring at 26 and 27. The bends 22 and 23 are preferably 85 spaced away from the marginal wall of the casing so that the resiliency of the spring will not be impaired by bearing against the side of the casing at these points. Similarly, the bends at 24 and 25 are also preferably 90 spaced away from the peripheral wall of the casing.

The spring may, if desired, be positioned 95 relative to its casing by a projection 31 extending within the curve of the spring adjacent its central portion 21.

When the head of the stud 6 is entered through the stud-receiving aperture 13 in the casing, the stud-engaging spring jaws 19 and 20 are spread apart and grip the neck 7 of the stud when the latter is fully entered 100 in the socket. The notch 18 in the socket is preferably adjacent the edge 30 of the socket-carrying fabric 15, so that the normal lateral strain between stud and socket will lead the neck of the stud into the notch 18. 105 When the stud is entered in this notch, the resolution of forces arising from lateral strain will not cause the stud to tip in such a way as to become separated from the socket. On the other hand, when it is de- 110

sired to separate the stud from the socket, a pull on either the stud or socket in either an axial direction or one producing a tip somewhat greater than that arising from the resolution of forces under lateral strain will cause the stud to be released from the socket even though a considerable amount of lateral strain between stud and socket exists at the time of separation.

10 While I have shown and described a preferred form of one embodiment of my invention, it will be understood that changes involving omission, substitution, alteration, and reversal of parts, and even changes in 15 the mode of operation, may be made without departing from the scope of my invention, which is best defined in the following claims.

Claims.

1. A snap fastener socket comprising, in combination, a casing providing a plate having a stud-receiving aperture therein and a spring in said casing formed of a single piece of wire providing two portions intersecting the stud receiving aperture, the spring between the said two portions extending adjacent to the peripheral wall of the casing, said spring, at the other side of said two portions, presenting two oppositely bent reverse curves spaced away from the peripheral wall of the casing, and said spring, beyond said reverse curves, engaging the peripheral wall of the casing.

2. A snap fastener socket comprising, in combination, a casing providing a plate having a stud-receiving aperture therein and a spring in said casing formed of a single piece of wire providing two portions intersecting the stud-receiving aperture, the spring between the said two portions extending adjacent to the peripheral wall of the casing, said spring, at the other side of said two portions, presenting two oppositely bent reverse curves spaced away from the peripheral wall of the casing, and said spring, beyond said reverse curves and at generally diametrically opposite points, engaging the peripheral wall of the casing.

3. A snap fastener socket comprising, in combination, a casing providing a plate having a stud-receiving aperture therein and a spring in said casing formed of a single piece of wire providing two portions intersecting the stud-receiving aperture, the spring between the said two portions extending adjacent to the peripheral wall of the casing, said spring, at the other side of said two portions, presenting two oppositely bent reverse curves spaced away from the peripheral wall of the casing, and said spring beyond said reverse curves presenting two additional reverse curves spaced away from the peripheral wall of said casing.

4. A socket for separable fasteners comprising a casing presenting a plate having

a stud-receiving aperture therein, said plate provided with a flanged-over rim, and a spring in said socket presenting two portions intersecting said aperture, said spring having at one side of said portions a part underlying said flanged-over rim, and at the other side of said portions two parts underlying said rim, said two parts 22, 23 spaced away from the peripheral wall of said casing to permit resilient movement of said two parts relative to each other and relative to said casing.

5. A socket for separable fasteners comprising a casing having a plate at one side with a stud-receiving aperture therein, the opposite side of said casing open but presenting a rim flanged-over from the peripheral wall of the casing, and a spring in said casing presenting a resiliently movable part underlying said rim but normally out of contact with the peripheral wall of said casing.

6. A socket for separable fasteners comprising a casing having a plate at one side with a stud-receiving aperture therein, the opposite side of said casing open but presenting a rim flanged-over from the peripheral wall of the casing, and a spring in said casing presenting four resiliently movable runs with three curved portions between them, all of said curved portions underlying said rim and at least two of said curved portions normally spaced away from the peripheral wall of said casing.

7. A socket for separable fasteners including a casing having a plate with a stud-receiving aperture therethrough, said plate notched at one side of said stud-receiving aperture to permit a limited lateral displacement of the stud, and a W-shaped spring in said casing.

8. A socket for separable fasteners including a casing having a plate with a stud-receiving aperture therethrough, said plate notched at one side of said stud-receiving aperture to permit a limited lateral displacement of the stud and a W-shaped spring in said casing, said spring having the bottom curves of the W disposed at each side of the notched portion of the plate.

9. A socket for separable fasteners including a casing having a plate with a stud-receiving aperture therethrough, said plate notched at one side of said stud-receiving aperture to permit a limited lateral displacement of the stud, and a W-shaped spring in said casing, said spring having the bottom curves of the W disposed at each side of the notched portion of the plate, and spaced away from the peripheral wall of said casing.

In testimony whereof, I have signed my name to this specification.

FRED S. CARR,
